UNITED STATES PATENT OFFICE.

WILLIAM PAWLAK, OF CHICAGO, ILLINOIS, ASSIGNOR TO JOHN F. GUBBINS, OF CHICAGO, ILLINOIS.

WRINGER-GUARD AND FEEDING DEVICE.

1,161,245.

Specification of Letters Patent. Patented Nov. 23, 1915.

Application filed February 25, 1915. Serial No. 10,589.

To all whom it may concern:

Be it known that I, WILLIAM PAWLAK, a citizen of the United States, residing at Chicago, in the county of Cook and State of Illinois, have invented certain new and useful Improvements in Wringer-Guards and Feeding Devices, of which the following is a specification.

This invention relates to a guard and hopper adapted for use with clothes wringers, and has for its object to provide improvements in safety attachments for wringers for preventing injury to the hands of the operators.

15 In the use of clothes wringers, especially those which are power-driven, it not infrequently happens that the hands of the operators are drawn between the rollers, while feeding clothes thereto, thereby causing serious injury before the operation of the rollers can be discontinued.

20 My invention comprises a guard or hopper adapted to be attached to a clothes wringer for guiding the clothes to the rollers thereof, thus obviating the necessity of, and the danger occasioned by, the operators placing their hands near the rollers. I have also provided means for positively feeding the clothes to the rollers in case they are not automatically drawn between the rollers upon being placed in the hopper.

25 Another object of the invention is to provide, in combination with the hopper, means for feeding clothes to the rollers of the wringer.

30 A further object is to provide improved means for readily attaching the hopper and the feeding means to the wringer at either side thereof.

35 These and other objects of the invention will be more particularly set forth in the following specification, taken in connection with the accompanying drawings, in which I have illustrated one form which the invention may take.

40 In the drawings, Figure 1 shows an end elevation of a wringer with my improved hopper and feeding means shown in section, and showing by dotted lines the position of my improvements at the other side of the wringer. Fig. 2 is a fragmentary side elevation of the wringer with my improvements attached thereto. Fig. 3 is a side elevation of one of the bracket members, by means of 45 which the hopper is attached to the wringer;

and Fig. 4 is a perspective view of a portion of the movable wall of the hopper.

Like reference numerals refer to like parts and elements in the several figures of the drawings.

50 The top cross member of the wringer, designated by the numeral 10, is secured at its ends in any suitable manner, as shown at 11, to the upper ends of the side frame members 12. The lower ends of the side members are recessed, as shown at 13, to engage the side of a wash tub or washing machine, or other suitable support. The usual clamp screw 14 is adapted to engage the portion of the support within the opening 13 in each side member 55 of the wringer frame, thereby holding the wringer rigidly in position.

55 The usual oppositely rotating rollers 15 and 16, between which the clothes pass and by which the water is squeezed out of the clothes, are journaled at their ends in bearings located within vertical slots in the side members of the supporting frame. A leaf spring 17 is located above the upper roller 15 and bears at its ends on the bearings of said 60 roller, whereby said roller is forced into yielding contact with the lower roller 16. The pressure with which the upper roller contacts with the lower roller is regulated by means of the adjusting screw 18, which 65

threadedly engages the top cross member at the center thereof and bears at its lower end on the upper surface of the spring 17. Beneath the rollers 15 and 16 there is located a board 19, which is pivoted at its ends in the 70 side frame members, as shown at 20, and is therefore capable of being inclined in either direction with respect to the vertical plane of the wringer. Below the board 19, and between the side frame members, is a rod 21, 75

which rigidly engages said side frame members by any suitable means, as shown at 22, and holds the lower ends of said members in fixed relation to each other. The lower side of the board 19 carries a leaf spring 23, which frictionally engages the rod 21, and thereby operates to hold said board at any desired inclination, in order to drain the water extracted from the clothes into any suitable vessel at either side of the wringer.

80 One end of the shaft of the roller 16 extends through the side frame and is operatively connected to a source of power. The shafts of the rollers 15 and 16 carry intermeshing gear wheels within the side frames,

whereby rotation is communicated from the lower to the upper roller—(not shown in the drawings).

The foregoing features do not in themselves constitute a part of my invention, since they are the parts of an ordinary wringer.

My invention comprises a combined guard and feeding hopper, designated generally by 10 the numeral 25, having end walls 26 and 27, and upper and lower walls 28 and 29, respectively, formed preferably of sheet metal. The upper wall 28 and the end walls 26 and 27 are rigidly connected by soldering or 15 other suitable connecting means, and the uppermost extremities of the end walls 26 and 27, opposite the wall 29, are supported and connected by a transverse member 30, whose upper edge is rolled, as shown at 31. The 20 lower wall 29 of the hopper is provided with a rolled lower edge 32, and the ends of this rolled portion are pivotally connected at 32^a to the lowermost portions of the end walls 26 and 27, so that the lower wall 29 25 may swing upwardly above said pivotal connection away from the transverse member 30. The lower wall is provided, adjacent the upper side thereof, with an outwardly bent portion 33, the outer edge of which is 30 rolled, as shown at 34, and to one end of said roll portion is rigidly connected a vertically extending handle 35.

To permit ready attachment of my hopper to a wringer, I have provided detachable 35 brackets 40, each of which has formed therein a rectangular slot 41, adapted to engage the cross member 10 of the wringer at the desired locations, and the walls of these slots are threadedly engaged by studs or 40 cap screws 42, which may be adjusted inwardly to engage the member 10, and thus hold the bracket in position. Each bracket is provided with a flange 43 extending from one side thereof transversely to said member 10, which flange is provided with an aperture 44. On the side thereof opposite the flange 43, each bracket is provided with an alining flange 45, which has formed thereon an upwardly turned hook 46. The brackets 45 are mounted on the wringer, so that the hook 46 of one bracket will be on the same side of the member 10 as the aperture 44 of the other bracket, as shown in Fig. 2, and one of the apertures 44 and the corresponding 50 hook 46 are adapted to be engaged by the studs 47 which project longitudinally from the upper rolled portion 48 of the upper wall 28 of the hopper. It will be apparent that one of the studs 47 may be readily 55 passed into the aperture 44, after which the other stud 47 may be brought into engagement with the hook 46. The hopper will then be pivotally mounted on the wringer, but in order to prevent it from swinging 60 away from the wringer, I prefer to employ 65

a leaf spring 50, which is riveted to the outer side of the upper hopper wall 28, and which extends upwardly into engagement with the middle portion of the cross frame member 10.

The end walls 26 and 27 have secured thereto projecting lugs 51, which engage adjacent portions of the wringer structure at the ends of the rollers and prevent contact of the hopper with the rollers while permitting 70 the desired close relation. It will be seen that the lugs 51 are so located, and other parts so constructed, that the lower wall 29 terminates adjacent the periphery of the lower roller, and for this purpose the end 75 walls are notched at 52.

It will be apparent from an inspection of the drawings that the end walls 26 and 27 of the hopper are parallel and in substantially vertical planes, while the upper and 80 lower walls 28 and 29 converge downwardly toward the rollers, so that clothes placed in said hopper will be directed downwardly toward the rollers. If it be found, however, that the clothes placed in the hopper are 85 not automatically drawn between the oppositely rotating rollers of the wringer, the operator may grasp the handle 35 and move the lower pivoted wall 29 of the hopper upwardly and inwardly toward the rollers 90 about its pivotal connections, and thereby force the clothes toward and between the rollers. It will, therefore, be apparent that there is no necessity for the operator placing 95 his hands within the hopper, or in proximity 100 to the rollers, so that my improved device substantially overcomes the danger which has hitherto been present in the operation of wringers.

When it is desired to use the wringer in a reverse manner, the hopper may be disengaged from its position by moving one of the studs 47 upwardly from the hook 46, and disengaging the other stud 47 from the aperture 44, after which the hopper may be 110 attached in the same manner at the other side of the wringer, as shown by dotted lines in Fig. 1. It will be evident that my device may be readily attached to substantially any 115 wringer.

My invention is capable of many modifications, and of various forms and arrangement of parts other than those illustrated and described, and I therefore do not wish to be limited in the scope of the invention, 120 except as defined by the appended claims.

I claim:

1. The combination with a clothes wringer comprising rollers, of a clothes-supporting member pivotally mounted below the line of contact of said rollers for positively feeding clothes thereto.
2. The combination with a clothes wringer comprising rollers, of a pivotally mounted member arranged to support the clothes and 130

- movable toward said rollers for feeding said clothes thereto.
3. The combination with a clothes wringer, of a hopper, and means acting positively to feed clothes from said hopper to said wringer.
4. The combination with a clothes wringer comprising rollers, of a clothes hopper, and means carried by said hopper and movable toward said rollers for feeding clothes thereto.
5. A device for feeding clothes to a wringer comprising a guide member downwardly inclined toward the rollers of said wringer and movable toward the same for positively feeding clothes thereto.
6. A wringer guard having upper and lower downwardly converging walls, and end walls, said lower wall being mounted to swing between said end walls.
7. A device for feeding clothes to a wringer comprising a plate pivotally mounted below the line of contact of the rollers of said wringer and inclined upwardly and outwardly therefrom.
8. The combination with a clothes wringer, of a hopper, a bracket detachably secured to said wringer, and means carried by said hopper for engaging said bracket at either side of the wringer.
9. The combination with a clothes wringer comprising rollers, side frame members, and a cross member, of a clothes feeding device, and a bracket attached to said cross member and engaging said clothes feeding device.
10. The combination with a clothes wringer comprising rollers, of a clothes feeding device, a bracket detachably secured to said wringer, and means carried by said clothes-feeding device for engaging said bracket.
11. The combination with a clothes wringer, of a clothes feeding device, means for pivotally attaching said device to said wringer, and means for preventing said device from swinging away from said wringer.
12. The combination with a clothes wringer, of a clothes feeding device, means for pivotally attaching said device to said wringer, and a clip attached to said device and engaging said wringer for preventing said device from swinging away from said wringer.
13. In a device of the class described, a pair of supporting members carried by a clothes wringer and projecting outwardly from each side thereof, said supporting members each having a notch therein at one side of said wringer, and an aperture therethrough at the other side of said wringer, the notch of one member being disposed oppositely to the aperture of the other member, a clothes-feeding device, and means carried by said clothes-feeding device for engaging a notch and an aperture in said members at either side of said wringer.

In testimony whereof I have subscribed my name.

WILLIAM PAWLAK.
